(57) **CLAIM**

The ornamental design for a hatchet head, as shown and described.

DESCRIPTION

FIG. 1 is a right side and top perspective view of a hatchet head showing my new design, wherein the broken line showing of the branch threaded into the opening to form a handle is for illustrative purposes only and forms no part of the claimed design.

FIG. 2 is a top plan view thereof;

FIG. 3 is a rear elevation view thereof;

FIG. 4 is a left side elevation view thereof;

FIG. 5 is a front elevation view thereof; and,

FIG. 6 is a bottom plan view thereof.
